UNITED STATES PATENT OFFICE.

GEORGE W. KNIGHT, OF HOPEDALE, MASSACHUSETTS, ASSIGNOR TO GEORGE DRAPER & SONS, OF SAME PLACE.

CLEANER FOR SPINNING-RING TRAVELERS.

SPECIFICATION forming part of Letters Patent No. 564,087, dated July 14, 1896.

Application filed January 2, 1896. Serial No. 574,045. (No model.)

To all whom it may concern:

Be it known that I, GEORGE W. KNIGHT, of Hopedale, county of Worcester, State of Massachusetts, have invented an Improvement in Cleaners for Spinning-Ring Travelers, of which the following description, in connection with the accompanying drawings, is a specification, like letters on the drawings representing like parts.

10 It has heretofore been found difficult to properly apply traveler-cleaners for spinning-rings either to the ring-holder or to the ring-rail, and in the various devices heretofore proposed for accomplishing the desired object it has been necessary sometimes to make the ring itself of a different form or to use other expensive mechanical means.

15 This invention has for its object the production of a simple and efficient traveler-cleaner and the means for applying and retaining it securely in place, as will be hereinafter described in the specification, and particularly pointed out in the claims.

20 Figure 1, in elevation, represents a spinning-ring and ring-holder with the traveler-cleaner applied thereto in accordance with my invention. Fig. 2 is a top or plan view of the parts shown in Fig. 1. Fig. 3 is a top view of the ring-holder and the traveler-cleaner, 25 the ring being omitted; and Fig. 4 is a sectional view taken on the line $x-x$, Fig. 2.

25 The spinning-ring a may be of any desirable construction, and is herein shown as provided with top and bottom flanges a' and a'' , respectively. The ring-holder b is shown as a preferably split or expandible ring, having an annular flange b' , shouldered at b^2 , to receive the lower flange of the spinning-ring, and having in its upper face an annular 30 groove or recess b^3 , over which the lower ring-flange a^2 extends when held in the holder. When the ring is inserted, the holder b is sprung or expanded sufficiently to receive it, and its resiliency, when released, grips the 35 lower flange of and holds the ring firmly in place.

40 As shown in the drawings, the traveler-cleaner consists of a piece of wire bent or upturned at c at the desired angle to properly

clean the traveler, the remainder of the wire 50 being shown in Fig. 3 as circularly curved at c' to enter the groove b^3 in the top of the holder. The upturned end c of the cleaner projects through the opening b^4 between the ends of the holder b , (see Figs. 1 to 3, 55 inclusive,) and preferably the said ends are beveled and non-radial, as shown best in Fig. 3.

When the cleaner is in place, as shown in Fig. 3, the spinning-ring is applied to the ring-holder b , and rests on the extended end 60 or base c' of the cleaner, retaining it firmly in place, and by preferably making the curved base c' greater than one hundred and eighty degrees it cannot be pulled out of the holder, so that there is no liability of its accidental 65 removal.

The ring-holder may be made continuous, if desired, and circumferentially slotted at its upper side to admit the end of the traveler-cleaner, without departing from the spirit 70 and scope of my invention.

I claim—

1. A spinning-ring, and an expansible non-radially-slotted annular holder therefor adapted to clamp the ring, combined with a 75 traveler-cleaner consisting of a piece of wire bent to form a circularly-curved base held throughout its extent between the holder and the foot of the ring, and upturned at its end and extended through the non-radial slot in 80 the ring-holder, substantially as described.

2. A spinning-ring, and an annular holder therefor provided with a circular groove or recess in its top, and circumferentially slotted, combined with a traveler-cleaner consisting of a wire bent to enter said circular groove and be retained therein by the ring, said wire being upturned at its outer end and extended through the slot in the holder adjacent the exterior of the ring, substantially as 90 described.

In testimony whereof I have signed my name to this specification in the presence of two subscribing witnesses.

GEORGE W. KNIGHT.
